UNITED STATES PATENT OFFICE.

ELMER S. ROBERTS, OF PHILADELPHIA, PENNSYLVANIA, ASSIGNOR TO HENRY DISSTON & SONS, INCORPORATED, OF PHILADELPHIA, PENNSYLVANIA, A CORPORATION OF PENNSYLVANIA.

DESIGN FOR A SCREW-DRIVER.

41,896.

Specification for Design.

Patented Nov. 7, 1911.

Application filed June 24, 1911. Serial No. 635,187. Term of patent 14 years.

To all whom it may concern:

Be it known that I, ELMER S. ROBERTS, a citizen of the United States, residing in Philadelphia, Pennsylvania, have invented a certain new, original, and ornamental Design for a Screw-Driver, of which the following is a specification, reference being had to the accompanying drawing, forming part thereof.

The figure is a perspective view of a screw driver illustrating my design.

I claim:

The ornamental design for a screw driver, as shown.

ELMER S. ROBERTS.
